INVENTOR

George W. Wright,
BY
Chester Bradford,
ATTORNEY.

UNITED STATES PATENT OFFICE.

GEORGE W. WRIGHT, OF LAPEL, INDIANA.

LAWN-COASTER.

SPECIFICATION forming part of Letters Patent No. 664,920, dated January 1, 1901.

Application filed July 2, 1900. Serial No. 22,349. (No model.)

To all whom it may concern.

Be it known that I, GEORGE W. WRIGHT, a citizen of the United States, residing at Lapel, in the county of Madison and State of Indiana, 5 have invented certain new and useful Improvements in Lawn-Coasters, of which the following is a specification.

This device is designed as a substitute for the ordinary double swing, which is much used for purposes of rest and recreation; and, generally speaking, it consists of a frame mounted on rollers, so as to be easily reciprocated back and forth, carrying the occupants in a horizontal instead of a curvilinear direction, thus differing from the swings above referred to. This forms, in effect, a riding-chair, which, as it is commonly used out of doors, I have denominated a "lawn-coaster," although it may be used indoors also, and when constructed of suitable size and style is appropriate for sitting-rooms and parlors.

Referring to the accompanying drawings, which are made a part hereof and on which similar reference characters indicate similar parts, Figure 1 is a perspective view of a double chair or "coaster" embodying my said invention; Fig. 2, an end elevation of the same on an enlarged scale; Fig. 3, a detail sectional view, as seen from the dotted line 3 3 in Fig. 1, on a still further enlarged scale; and Fig. 4 is a fragmentary horizontal sectional view as seen when looking downwardly from the dotted line 4 4 in Fig. 1.

In detail this apparatus has a base 1, constructed in any suitable manner, preferably from timbers and boards, and which is designed to be stationary. Its top constitutes the floor upon which the feet of the occupants rest when the device is in use. Secured to this base 1 are four roller-housings 2, which contain the rollers or trucks 3, upon which the movable frame rests. These housings, as best shown in Fig. 3, are bifurcated, the two sides being that distance apart which is capable of receiving the rails of the movable frame. They are also horizontally slotted and receive the gudgeons of the antifriction trucks or rollers 3, while the peripheries of said rollers come in contact with the rails of the movable frame above referred to. These

trucks or rollers therefore provide both a means for securing the easy reciprocal movement of the movable frame and a means for holding it securely in place, so that it cannot tip out of position in case one end or the other 55 of the structure should be overbalanced.

The reciprocating framework is composed of suitable bars 4, 5, 6, 7, and 8, bolted or otherwise secured together, the bars 4 and 5 respectively passing above and below the trucks 60 or rollers 3, as shown. Connected to the cross-bars 7 of the reciprocating frame and to the floor of the base 1 are torsional springs 9, which aid in returning the reciprocating frame to a central position after it has been 65 pushed endwise by the occupant. These springs I have found in practice to add considerably to the desirability of the apparatus.

The seats are formed by securing to cross-bars 10 and 11 of the reciprocating frame a 70 suitable piece of fabric 12, which, as shown in Fig. 1, makes a comfortable and desirable seat.

In use the one or two occupants after seating themselves in this apparatus push gently 75 with their feet upon the base 1, which drives the reciprocating frame back and forth, the motion being aided, as above stated, by the springs 9.

Having thus fully described my said invention, what I claim as new, and desire to secure by Letters Patent, is—

1. The combination of a base, roller-housings mounted on said base, rollers mounted in said housings, a movable frame mounted 85 on said rollers, springs connecting said movable frame to said base, and seats mounted in said movable frame.

2. The combination of a base, roller-housings carried by said base, rollers mounted in 90 said housings, and a reciprocating movable frame adapted to carry occupants of the apparatus mounted on said rollers, said frame having duplex bars at the bottom passing both above and below the rollers, whereby said 95 frame is securely held from accidental disengagement, substantially as shown and described.

3. The combination, of a base, a movable frame mounted thereon, seats for occupants 100

in said movable frame, and torsional springs connected to cross-bars on the ends of the frame at one end and extending in and connected to said base at the other end and thus 5 adapted to aid in the reciprocal movement of the movable frame, substantially as set forth.

In witness whereof I have hereunto set my

hand and seal, at Lapel, Indiana, this 30th day of June, A. D. 1900.

GEORGE W. WRIGHT. [L. S.]
